(57) **CLAIM**

The ornamental design for an earbud adapter, as shown and described.

DESCRIPTION

FIG. 1 is a front perspective view of the earbud adapter embodying the new design;
FIG. 2 is a top view thereof;
FIG. 3 is bottom view thereof;
FIG. 4 is a rear view thereof;
FIG. 5 is a front view thereof;
FIG. 6 is a right side view, the left side being a mirror image thereof;
FIG. 7 is a bottom perspective view thereof; and,
FIG. 8 is a bottom perspective view thereof showing an earbud in broken lines for environmental purposes.
FIGS. 1-8 show portions of the earbud adapter in broken lines. The portions shown in broken lines do not form part of the claimed design.

1 Claim, 5 Drawing Sheets(56)
